UNITED STATES PATENT OFFICE.

WENSEL MORAVA, OF CHICAGO, ILLINOIS.

COTTON-BOLL-RIPENING APPARATUS.

Application filed July 19, 1920. Serial No. 397,527.

To all whom it may concern:

Be it known that I, WENSEL MORAVA, a citizen of the United States, residing at Chicago, in the county of Cook and the State of Illinois, have invented certain new and useful Improvements in Cotton-Boll-Ripening Apparatus, of which the following is a specification, reference being had to the accompanying drawings, forming a part thereof.

The purpose of this invention is to provide a process and an apparatus for ripening cotton bolls which are gathered before the bolls are open, to cause them to open for separation of the fiber. The process consists in the steps described and set out in the claims for the process, and the invention in the apparatus consists in the elements and feature of construction shown and described, as indicated in the claims.

The process of ripening the cotton bolls which constitutes that part of this invention, consists in accumulating and confining the bolls in a pile which is adapted to be replenished at the top, and diminished by discharge of the bolls laterally from the bottom, supplying heat underneath the pile to ripen the bolls at the bottom of the pile, and facilitating their discharge laterally from under the bottom of the pile as they are thus ripened and expanded, that is to say, supplementing the tendency of their expansion to discharge the bolls laterally, by mechanical assistance to their discharge, so that, the pile subsiding as the ripened bolls are discharged from the bottom and being replenished at the top, the process may be a continuous one, so long as the supply of bolls to be ripened lasts.

In the drawings there is shown an apparatus for practicing this process.

Figure 1 is a vertically axial section of a receptacle equipped with the means constituting this invention, and for practicing the process described.

Figure 2 is a section at the line, 2—2, on Figure 1.

The receptacle, 1, is preferably frusto-conical in form as shown, open at the top for receiving the bolls with which the receptacle is to be charged, and having at the bottom a short cylindrical terminal portion, 2, in which at a few inches below the end of the conically tapered part there is positioned a perforated bottom, 3, which is preferably, as shown, conical or frusto-coni-

cal, co-axial with the frusto-conical receptacle, 1. In the portion of the cylindrical bottom member, 2, extending above the plane of junction of the perforated bottom therewith, there are provided a plurality of discharge openings, 4, 4, 4, 4, for which closures, 5, 5, 5, 5, may be provided, adapted to be secured in closed position and opened at will as by sliding up in guide ways as shown, for discharging the material. From the lower margin of these openings, 4, 4, 4, 4, there is extended the frusto-conical shedding lip, 6, and on this lip there are mounted guide flanges, 7, 7, converging from the remote end of the two consecutive openings at each side of a vertical diametric plane of the device, to a common discharge chute, 8, so that the material discharge from the four openings, 4, 4, 4, 4, is gathered into two receptacles, 9, 9, to which said chutes, 8, 8, discharge.

In the base of the structure below the conical bottom, 3, there is located any suitable heating means, which is indicated in the drawings by steam or hot water circulating pipe, 12, by which the desired temperature may be maintained. The bottom, 3, is preferably perforated and air inlets are preferably provided as shown at 13, 13, 85 around the bottom of the structure so that the warm air from around these pipes is circulated up through the perforations of the bottom to affect the bolls which form the bottom of the pile resting upon said perforated bottom.

The mode of use of this apparatus is that the unopened cotton bolls which are to be ripened or dried out so as to cause them to open, are accumulated in the receptacle which is charged through the top opening, 1^a, the receptacle being filled to any desired height or to any height found most effective in respect to applying proper weight and avoiding excessive weight of the superincumbent quantity upon the portion at the bottom of the pile, resting immediately upon the bottom of the receptacle, and with respect to obtaining proper ventilation through the pile for the circulation of the warm air upward. At the beginning of the operation, the closures, 5, of the discharge opening, 4, will be closed for an adequate length of time to permit the ripening of the bolls at the lower part. After a certain length of time, which will vary according to the condition of the bolls from

2

a few hours to an entire day or more, the closures, 5, may be opened and the bolls allowed to escape as they will to some extent under the pressure of a super-incumbent quantity. It may be found under some conditions that the bolls become interlocked by the pressure to such an extent that they will not be discharged by gravity upon the opening of the doors, 5, and there is therefore 10 provided a discharging device consisting of a shaft, 16, journaled vertically in the bottom member, 3, and emerging at the center thereof, that is, at the apex when the bottom is of conical form, a lower journal bearing being provided at 17, and means for rotating it from the outside, as, for example, by a bevel gear, 18, on the lower end of the shaft, 16, connecting with a bevel gear, 19, on the inner end of a horizontal 15 shaft, 20, at the outer end of which there may be secured means for rotating it, as a crank, 21, or a belt-driven pulley, 22. To the upper end of the shaft above the bottom member, 3, there are secured sweeps, 25, which extend out along the upper surface of the bottom, 3, trending from the shaft outward and back in the direction of rotation of the shaft, so that as the shaft rotates, the sweeps crowd the material lying on the bottom outward along said bottom to the discharge apertures, 4.

I claim:—

1. An apparatus for ripening cotton bolls, comprising a vertically-extended receptacle 35 for containing a pile of the bolls; a heating means at the bottom of the receptacle; the receptacle having a charging opening at the top and a discharging opening at the bottom, and means for facilitating the discharge of the bolls from the bottom of the pile under the super-incumbent weight thereof.
2. In the construction defined in claim 1 foregoing, the receptacle being tapered narrowing from the bottom upward, and a tapered spreading device, centrally situated at

the bottom for deflecting the bolls outward at the bottom of the pile.

3. In the construction defined in claim 1 foregoing, closures for the discharge openings, adapted to be opened at will for intermittent discharge of the ripened bolls.

4. In the construction defined in claim 1 foregoing, the discharge-facilitating means comprising a rotary discharge device mounted for rotation horizontally at the plane of the discharge openings.

5. In the construction defined in claim 1 foregoing, the discharge-facilitating means comprising a rotary discharge device mounted for rotation horizontally at the plane of the discharge openings, and comprising sweeps deflected from the center of rotation outward and backward with respect to the direction of rotation, for giving the material an upward movement by means of the rotary movement of the sweeps.

6. In the construction defined in claim 1 foregoing, the receptacle having a perforated bottom, the discharge openings being above the bottom, and the heating means being located below said perforated bottom.

7. In the construction defined in claim 1 foregoing, the bottom of the receptacle being substantially conical for deflecting the material outwardly from the pile toward the discharge opening.

8. In the construction defined in claim 1 foregoing, the bottom of the receptacle being substantially conical for deflecting the material outwardly from the bottom of the pile toward the discharge opening, and a rotary sweep having its shaft at the cone axis, and sweep arms extending along the conical slope, each with a trend rearward with respect to the direction of rotation of the sweeps.

In testimony whereof, I have hereunto set my hand at Chicago, Illinois, this 13th day of July, 1920.

WENSEL MORAVA.
